UNITED STATES PATENT OFFICE.

OLIVER D. H. BENTLEY, OF NORFOLK, MASSACHUSETTS, ASSIGNOR TO B. F. STURTEVANT COMPANY, OF HYDE PARK, MASSACHUSETTS, A CORPORATION OF MASSACHUSETTS.

ELASTIC-FLUID TURBINE.

Application filed August 18, 1923. Serial No. 658,131.

The present invention relates to elastic fluid turbines and more especially to turbines designed for idling at low speeds.

In certain industries it is desirable to provide elastic fluid turbines which will idle economically at speeds considerably lower than the normal running speed. This is particularly true in gas producer work where a turbo blower is used to force a draft of air 10 through the generator. The blower runs only intermittently, being kept at full speed for a short period of time in order to force the air through the generator, after which the blower is shut down to allow production 15 of the gas in the usual manner. When the blower is not being run at full speed, it is desirable to have it idling at a relatively low speed, not only in order to maintain a sufficient pressure to prevent dangerous leakage of the combustible gases back into the 20 blower system, but also to keep the turbine thoroughly heated and in proper condition for immediate operation at full speed and efficiency. The usual practice for causing 25 the turbo blower to idle at low speeds consists merely in throttling the turbine steam supply down to a low pressure. For example, for a turbine running at full load under a pressure of one hundred and fifty 30 pounds the steam would be throttled down to approximately fifteen pounds in order to permit the blower to idle at approximately ten to fifteen per cent of normal full load speed. The design of the turbine nozzles is 35 such, however, that idling at such low pressures is extremely inefficient. Accordingly, it has been the practice to compromise between the high and low pressures and to provide nozzles designed for an intermediate 40 pressure, say one hundred and twenty-five pounds. This improves the idling efficiency slightly, but only at the expense of the running efficiency, since a nozzle will not operate at a pressure higher than that for 45 which it is designed without excessive losses due to eddying.

The object of the present invention is to provide a turbine which has provision for idling at low speeds and which will run 50 economically and at high efficiency at both high and low speeds. To this end the invention consists in the turbine hereinafter described and particularly defined in the claims.

The preferred embodiment of the present 55 invention contemplates the provision of a turbine having a plurality of nozzles all properly designed for operation under normal steam pressures, together with means for supplying the steam or other working fluid to all of the nozzles for operating the turbine under normal running conditions, and means for supplying the working fluid at normal steam pressure to only a portion 60 of the nozzles for the purpose of idling at a lower speed. Thus during full speed operation all of the nozzles are fed with the working fluid at substantially the high pressure of the supply and expand the fluid to 65 the pressure determined by the conditions within the turbine casing, whereas during idling the fluid is expanded only through the idler nozzle or nozzles but still between the same pressures. Each nozzle, therefore, 70 being designed for the same degree of expansion, will operate with full efficiency, 75 both at full load and also at idling speeds.

In the accompanying drawings illustrating the preferred form of the invention Fig. 1 is an elevation, partly in section, of the improved turbine; Fig. 2 is an end elevation of the turbine; Fig. 3 is an enlarged section on line 3-3 of Fig. 1; and Fig. 4 is an elevation of a power unit employing the improved turbine in connection with a fan or 80 blower.

The invention is herein illustrated and described as embodied in a turbine adapted to run a blower for gas producer work. The complete assembly is illustrated in Fig. 4 90 which shows a turbo blower comprising a turbine 6 and a blower 8 connected through the shaft 10, which is journaled in end bearings 12 and 14. The turbine comprises a rotor or bucket wheel 16 mounted upon the 95 shaft 10 and provided with a series of peripheral buckets 18 of the usual form. The rotor is enclosed by a turbine casing 20 having suitable exhaust port 22.

A series of regularly disposed nozzle segments are mounted in a manner to direct the steam to the bucket wheel. The illustrated embodiment of the invention employs eight nozzle segments, of which seven (indicated at 24) are secured to an incomplete 100 annular steam chest 26, which in turn is secured to the turbine casing. The eighth nozzle segment, 27, which may be termed the 105

"idler segment", is secured to a separate steam chest 28 which is also secured to the turbine casing. The nozzle segments are of any usual or preferred form having a flange 30 for bolting to the steam chest, a nozzle opening having the proper expansion ratio for the predetermined steam pressures and a plurality of reversing buckets 34.

The nozzles 24, which for convenience may be referred to as the power nozzles, are provided with throats or passages of large capacity so as to admit steam to almost the full capacity of the bucket wheel. Each nozzle is provided with the usual hand actuated valve 36 by which the passage of steam from the steam chest to the nozzle may be controlled. The steam is supplied to the chest 26 from any convenient source through a pipe line 38 which is connected to the steam chest by a coupling 40. The supply of steam to the chest is controlled by a governor valve 42 and a quick acting valve 44. The governor valve is actuated upon changes of speed through a governor 46 of the general type described in the Bentley Patent No. 1,103,024, mounted at the end of the turbine shaft. The quick acting valve 44 is operated so as to cut the steam suddenly off from the steam chest and is preferably actuated through a remote control indicated generally at 48 from the gas producer.

The idler nozzle 27 is provided with a throat or passage smaller than those of the power nozzles, but having the same expansion ratio. The size of the idler nozzle is such that just enough steam will be delivered at the normal steam pressure to drive the turbine and blower at the predetermined idling speed. The idler steam chest 28 is fed from the pipe line 38 through a pipe 50 which is coupled to the pipe line at 52 and to the steam chest at 54 and which bypasses both of the controlling valves 42 and 44 so that the latter have no effect upon the admission of steam to the idler nozzle.

Under running conditions steam is supplied to all of the nozzles at the original high pressure of the source, except for such slight variations as occur through the action of the governor valve. After the producer has run from three to five minutes the quick acting valve 44 is closed, thereby permitting the passage of steam only to the idler nozzle. Since the load upon the blower increases rapidly with the speed, it will be apparent that the greatly reduced amount of steam now presented to the turbine will be effectual only to rotate the unit at a considerably reduced speed. In practice it is desirable to have the turbo blower idle at approximately fifteen per cent. of full load speed, this being fast enough to build up sufficient pressure to prevent any dangerous back leakage of the combustible gases from the producer. The steam consumption neces-

sary to rotate at this speed is only about three or four per cent of normal steam consumption.

During the normal full load operation of the turbine, the seven nozzles 32 furnish the greater part of the power to the rotor. The idling nozzle, however, contributes to the operation at such time delivering its smaller amount of steam at the same high efficiency as the power nozzles and without unbalancing the turbine or otherwise detracting from the economy of its performance. When the valve 44 is closed the turbine idles by the steam supplied through the idling nozzle 33 with the same high efficiency. It has been found that this idling nozzle takes only about one-quarter of the amount of steam required where the steam is simultaneously throttled at all the nozzles. Since all the nozzles are designed properly for the pressures with which they are to be used, the turbine also runs with maximum efficiency at the high speeds and full power, as distinguished from the inefficient performance of variable pressure turbines which employ over-expanded nozzles as a compromise between the running and idling pressures.

While in the foregoing specification and drawings there has been described and illustrated what is now considered to be the preferred embodiment of the present invention, wherein the elastic fluid is supplied to all of the nozzles, both the power and the idling nozzles, at the same pressure, it is to be understood that the present invention is not necessarily limited to such a construction and arrangement but may, except where so specifically limited in the claims, be embodied in other constructions and arrangements.

Having thus described the invention what is claimed is:

1. A turbine having, in combination, a rotor, a nozzle of large capacity, a nozzle of small capacity, both nozzles having the same expansion ratio, means for supplying working fluid to the larger capacity nozzle, controlling means for the fluid supply, and means for supplying working fluid to the smaller capacity nozzle at the same pressure but independently of the said controlling means.

2. A turbine having, in combination, a rotor, a plurality of power nozzles, means including a single cut off valve for supplying working fluid to said nozzles, an idling nozzle of less capacity than the power nozzles, and means for supplying working fluid to the idling nozzle when the fluid is cut off from the power nozzles.

3. A turbine having, in combination, a rotor, a power and an idling nozzle, a governed steam supply for the power nozzle, an ungoverned steam supply at the same pressure for the idling nozzle, and means

for shutting off the governed supply to permit the fluid to pass only through the idling nozzle.

4. A turbine having, in combination, a plurality of nozzles all with the same expansion ratio, the majority of which are of greater capacity than the remainder, two sources of supply for delivering the working fluid at the same pressure, one for one set of nozzles and the other for the remainder, and speed controlled means for cutting off the source of supply from the first mentioned set of nozzles, whereby the turbine will operate normally with all the nozzles in action and will idle with the first mentioned set of nozzles out of action.

5. A power unit having, in combination a rotary blower, a turbine having power and idling nozzles, a steam supply for the nozzles, a common connection from the steam supply to the power nozzles, a valve in the connection, a direct connection from the steam supply to an idling nozzle and by-passing the said valve, whereby the steam may be supplied to all the nozzles for running the blower under load at normal speed and only to an idling nozzle when the valve is closed for driving the blower at low speed.

6. A turbine having, in combination, a rotor, a plurality of nozzles, a common steam chest for the majority of the nozzles, and a separate steam chest for the remainder, and means for controlling the supply of steam to the common steam chest only.

7. A turbine having, in combination, a rotor, a plurality of nozzles, a common steam chest for all but one of the nozzles, a steam supply line for the common steam chest, a valve in the supply line, and a connection from the supply line to the remaining nozzle and by-passing the valve in a manner to allow idling of the turbine through the single nozzle when the valve is closed.

8. A turbine having, in combination, a plurality of nozzles, one of the nozzles being smaller than the remaining nozzles, a

steam chest for the smaller nozzle, and a common steam chest for the remaining nozzles.

9. A turbine having, in combination, a rotor, a plurality of nozzles, a steam line, a main connection from the steam line to the majority of the nozzles, means for cutting off the steam in the main connection, and a connection from the steam line to the remainder of the nozzles and by-passing the cut-off means so that steam may be supplied only through the second connection for idling.

10. A turbine having, in combination, a rotor, a series of nozzles including a plurality of power nozzles and an idling nozzle of smaller size, means for supplying steam to all the nozzles when the turbine is running under a load, and means for supplying steam only to the idling nozzle but at the same pressure for idling.

11. A turbine having, in combination, a series of nozzles including a plurality of power nozzles and an idling nozzle of different size from the power nozzle, all of the nozzles being designed for expansion between the same pressures, means for supplying steam to the power nozzles, a governor and a cut-off valve for controlling the flow of steam to the power nozzles, and a separate steam connection to the idling nozzle which by-passes the governor and the cut-off valve, whereby steam may be supplied only to the idling nozzle, but at normal pressure when the cut-off valve is closed.

12. A turbine having, in combination, a rotor, a power nozzle, an idling nozzle, means for supplying elastic fluid to the power nozzle at the proper pressure for the expansion ratio of the nozzle, devices for cutting off the supply of elastic fluid to the power nozzle to permit the turbine to idle and connections for supplying elastic fluid to the idling nozzle at the proper pressure for the expansion ratio of said nozzle when the supply to the power nozzle is cut off.
